UNITED STATES PATENT OFFICE.

FRANK ZALESKI, OF SOMERVILLE, MASSACHUSETTS, ASSIGNOR TO THE REECE BUTTON HOLE MACHINE COMPANY, OF BOSTON, MASSACHUSETTS, A CORPORATION OF MAINE.

THREAD CUTTER AND CLAMP FOR SEWING-MACHINES.

1,216,537.

Specification of Letters Patent. Patented Feb. 20, 1917.

Application filed January 8, 1916. Serial No. 71,080.

To all whom it may concern:

Be it known that I, FRANK ZALESKI, a subject of the Emperor of Germany, residing at Somerville, county of Middlesex, 5 State of Massachusetts, have invented an Improvement in Thread Cutters and Clamps for Sewing-Machines, of which the following description, in connection with the accompanying drawing, is a specification, like 10 characters on the drawing representing like parts.

This invention relates to a thread cutter and clamp for sewing machines and has for its object to provide an improvement upon 15 the device shown in my co-pending application Se. No. 67,695, filed December 20, 1915. The device shown in said application is adapted for use in connection with a buttonhole sewing machine of that type 20 illustrated in United States Patent No. 494,280, March 28, 1893, or United States Patent No. 1,030,589, June 25, 1912, wherein the stitch-forming mechanism and work-clamping means have a movement relative to 25 each other to carry the parts from button-hole-cutting to buttonhole-stitching position and vice versa, and also to give the work a feeding movement during the stitching operation, and it comprises a thread-clamping means 30 device carried by the work-clamping means and rendered operative to clamp the thread by the relative movement between the stitch-forming mechanism and work-clamping means when the parts are being carried from 35 buttonhole-stitching to buttonhole-cutting position, said thread-clamping device retaining its hold on the thread until the parts have been moved into buttonhole-stitching 40 position again and the initial stitches are being formed, at which time the thread clamp releases the needle thread. The thread clamp shown in said application is in the 45 form of two thread-clamping jaws movable relative to each other, and one of said jaws has a thread-cutting blade rigid therewith so that when the jaws are closed to clamp the thread, the thread will be cut.

I have found from experience that a 50 thread cutter rigid with one of the clamping jaws is not always certain in operation because it does not always act with the same certainty on threads of different sizes and character, some threads being cut perfectly and other threads being only partially cut.

My present invention aims to provide a 55 novel thread cutter adapted to be associated with the device illustrated in the above-mentioned application by which the thread will be cut with certainty and accuracy immediately after it has been clamped by the 60 clamping device, regardless of the size or character of the thread. I secure this end by providing a thread-cutting device which is operable independently from the thread-clamping jaws and which is constructed to 65 be actuated to sever the thread immediately after it has been clamped by the same means which actuates the thread-clamping device.

In order to give an understanding of my invention I have illustrated in the drawings 70 a selected embodiment which will now be described after which the novel features will be pointed out in the appended claims.

Figure 1 of the drawings is a partial 75 side view of a portion of a buttonhole sewing machine such as illustrated in my said co-pending application and having my improvements applied thereto;

Fig. 2 is a plan view of the work holder and the thread clamping and cutting device; 80

Fig. 3 is an end view.

Inasmuch as my invention relates simply to the thread cutter and clamp, I have deemed it necessary to illustrate only that portion of the sewing machine to which the 85 clamp and cutter is applied and by which it is actuated.

1 indicates the bed plate of a sewing machine from which rises the usual overhanging arm 2 carrying the upper thread-handling mechanism herein shown in the form of a reciprocating needle bar 3 carrying an eye-pointed needle 4. This needle cooperates with the under thread-handling mechanism (not shown) to concatenate the edge 90 stitches of the buttonhole, as usual in sewing machines of this type. 5 indicates work clamps which are carried by arms 6 that are pivotally mounted on clamp plates 8 on which the work *w* is placed. These clamps 100 5 are elevated from the clamp plates 8 when the machine is at rest, as shown in Fig. 1 to permit the work to be inserted, and when the machine is started they are automatically moved downwardly into engagement 105 with the work to clamp the latter in position. 9 indicates the buttonhole cutter by which the buttonhole is cut. The above-

described parts are such as are usually found in buttonhole sewing machines and form no part of the present invention.

The work-clamping means comprising the 5 clamp plates 8 and work clamps 5 and the stitch-forming mechanism are constructed to have a movement relative to each other during each cycle of operations, and in the 10 particular machine herein illustrated, this 10 relative movement is secured by giving movement to the work-clamping means by means of a feed cam shown in dotted lines at 10. When the machine is brought to rest at the end of each cycle of operations 15 parts are in buttonhole-cutting position, as shown in Fig. 1, and the work clamps 5 are raised. When the machine is started, the work clamps are first depressed to clamp the work *w* against the clamp plates, and then 20 the cutter 9 operates to cut the buttonhole. Thereafter the feed cam 10 moves the work-clamping means relative to the stitch-forming mechanism to carry the work from buttonhole-cutting to stitching position and 25 the stitching begins, the work-holding means having a continued feeding movement to effect the formation of the stitches around the edge of the buttonhole. When the stitching has been completed around the button- 30 hole, the stitch-forming mechanism is brought to rest, and the work-holding means and stitch-forming mechanism have a further relative movement to carry the parts from stitching to buttonhole-cutting posi- 35 tion.

The thread clamp which is illustrated in my above-mentioned co-pending application is carried by the movable work clamps and is actuated to clamp the needle thread *t* at 40 the end of the stitching operation and while the parts are moving from stitching to buttonhole-cutting position. This thread-clamping device comprises a fixed clamping jaw 13 and a movable clamping jaw 14. The 45 fixed jaw 13 is carried by an arm 15 which is made rigid with one of the arms 6 by means of a screw 16. The movable jaw 14 is carried by a lever 17 which is pivoted on a stud 18 secured to the arm 15. This arm 50 17 has a pin 20 rising therefrom which is acted upon by a suitable spring 19, said spring tending to hold the clamping jaws 13 and 14 closed. The lever 17 is provided with a cam projection 21 adapted to engage 55 a roll 22 on the end of a lever 23 which is pivoted at 24 to a base plate or support 29 that in turn is secured to the frame 1. This lever 23 has a finger 25 extending therefrom which plays between two adjustable stop 60 screws 26, 27. During the stitching on the buttonhole, the work-clamping means is so position that the roll 22 will be at the right on the cam projection 21 and the stop screws 26, 27 are so adjusted that when the parts 65 move from the stitching to buttonhole-cut-

ting position after the end of the stitching operation, the cam projection 21 will strike the roll 22, as shown in Fig. 2, thereby opening the clamping jaws and permitting the needle thread to pass between said jaws as 70 the work clamp is moved backwardly. Before the parts reach buttonhole-cutting position the roll 22 has passed the cam projection 21, thus allowing the clamping jaws to close under the influence of the spring 19 75 and clamping the needle thread, as shown in Fig. 1. When the machine is started again and the work-clamping device is moving from buttonhole-cutting to stitching position, the cam 21 will engage the roll 22 80 and swing the lever 23 so as to carry the finger 25 against the stop 26. Said stop is so adjusted that the finger 25 will be brought into engagement therewith just as the first stitches on the buttonhole are being formed 85 and as the work clamp continues its movement toward the left Fig. 2, the engagement of the cam 21 with the roll 22 will open the jaws to release the thread, this occurring just as the initial stitches are being formed. 90 The thread-clamping device as above described is such as is illustrated and described in my said co-pending application.

By my present invention I have provided a thread-cutting device which is independent from the thread-clamping means and which is actuated by the lever 23 to cut the needle thread after it has been clamped. My improved thread-cutter is shown as a cutting blade 30 which is carried on an 10 arm or lever 31 that is pivoted to the work clamps. One convenient way of accomplishing this is to pivotally mount the arm 31 on the same stud 18 on which the lever 17 is pivoted. This arm 31 is shown as acted 105 upon by a spring 32 which normally holds the cutting blade in its retracted position, and said arm 31 has also mounted thereon a roll 33 situated to be engaged by the roll 22 during the movement of the work-holding means from stitching to buttonhole-cutting position and immediately after the roll has acted on the projection 21. In the operation of the device when the stitching on the buttonhole has been completed, the stitching mechanism is brought to rest with the needle raised as usual, and the work-clamping means then moves toward the right, Fig. 2. During this movement the projection 21 engages the roll 22 and opens the 110 thread-clamping jaws as shown in Fig. 2, and as the projection wipes by the roll, the jaws will close onto the thread which has been drawn between them by the movement of the work clamps, thereby clamping the 115 thread. Immediately after the thread is clamped the continued movement of the work-clamping means brings the roll 33 against the roll 22 thereby giving a quick forward movement to the arm 31 and caus- 120 125 130

ing the cutting edge 35 of the cutting blade 30 to be carried against the thread extending between the thread clamp and the work. This portion of the thread will be held taut so that the movement of the cutting blade against it will sever it accurately and with certainty regardless of the size or character thereof. It will thus be seen that the thread-cutting device is separate from the thread clamp and is operated subsequently to the clamping of the thread. It will also be seen that said thread-cutting device is actuated by the same means that controls the movement of the thread clamp, this means acting first to effect the clamping of the thread and then the cutting thereof.

I claim:

1. In a sewing machine, the combination with stitch-forming mechanism, of work-clamping means, said stitch-forming mechanism and work-clamping means having a movement relative to each other during a predetermined cycle of operations including a stitching operation, a thread clamp 25 carried by said work-clamping means above the work, a cutter separate from the thread clamp, and means rendered operative by such relative movement to cause the thread clamp to clamp the thread at the end of the 30 stitching operation and then to actuate the cutter to cut the thread.

2. In a sewing machine, the combination with stitch-forming mechanism, of work-clamping means, said stitch-forming mechanism and work-clamping means having a relative movement during a predetermined cycle of operations including a stitching operation, a pair of thread-clamping jaws carried by the work-clamping means above the 40 work, a thread cutter separate from said jaws, and means rendered operative by such relative movement to cause the thread-clamping jaws to clamp the thread at the end of the stitching operation and subsequently to actuate the cutter to cut the clamped thread.

3. In a sewing machine, the combination with stitch-forming mechanism, of work-clamping means, said stitch-forming mechanism and work-clamping means having a movement relative to each other during a predetermined cycle of operations including a stitching operation, two movable elements, one adapted to clamp and the other to cut 55 the needle thread above the work held in the work-clamping means and means to actuate said elements successively at the end of the stitching operation whereby the thread will be first clamped and then cut.

4. In a buttonhole sewing machine, the combination with stitch-forming mechanism including a reciprocating eye-pointed needle, of work-clamping means, means to give the work-clamping means a work-feeding movement while the edge stitches on a buttonhole

are being formed and an additional movement after the stitching on a buttonhole is completed to carry the work into button-hole-cutting position, a thread-clamping device carried by the work-clamping means 70 above the work, a thread-cutting device independent of the thread-clamping device, and an actuating device rendered operative by the movement of the work-clamping means to cause the thread clamp to clamp 75 the thread at the end of the stitching operation and subsequently to actuate the cutter to cut the thread.

5. In a buttonhole sewing machine, the combination with a frame carrying stitch-forming mechanism, of work-clamping means, means to move the work-clamping means on the frame thereby to move the work carried thereby from stitching to button hole-cutting position, a fixed and a movable thread-clamping jaw mounted on the work-clamping means above the work held in the work-clamping means, a thread cutter independent from said jaws and also mounted on said work-clamping means, and 85 an actuator carried by said frame and operating during said movement of the work-clamping means to cause the thread-clamping jaws to clamp the thread and subsequently to actuate the cutter to cut the 90 clamped thread.

6. In a buttonhole sewing machine, the combination with a frame carrying stitch-forming mechanism, of work-holding means, means to move the work-holding means on the frame thereby to move the work from stitching to buttonhole-cutting position, a fixed and a movable thread-clamping jaw mounted on the work-holding means, a cam projection rigid with the movable jaw, a 100 swinging cutting blade separate from said thread-clamping jaws, and an actuator carried by said frame and adapted to engage said cam projection and actuate the movable thread-clamping jaw and subsequently to 110 actuate the thread cutter.

7. In a buttonhole sewing machine, the combination with a frame carrying stitch-forming mechanism, of work-clamping means, means to give the work-clamping means a movement relative to the frame to carry the work from stitching to button-hole-cutting position, an arm pivoted to the work-clamping means and carrying a thread-clamping jaw, said arm having a cam 115 projection, a second arm pivoted to said work-clamping means and carrying a cutting blade, said arm also having a projection, and an actuator carried by said frame and adapted to engage said projections successively during the movement of the work-clamping means thereby to clamp 120 and cut the thread successively.

8. In a buttonhole sewing machine, the combination with a frame carrying stitch- 130

- forming mechanism, of work-clamping means, means to move the work-clamping means on the frame thereby to move the work carried thereby from stitching to buttonhole-cutting position, a fixed and a movable thread-clamping jaw mounted on the work-clamping means, a thread cutter independent from said jaws also mounted on said work-clamping means, and an actuator carried by the frame and capable of having a limited free movement in the direction of movement of the work-clamping means and operating during said movement of the work-clamping means to cause the thread-clamping jaws to clamp the thread and subsequently to actuate the cutter to cut the clamped thread.
9. In a buttonhole sewing machine, the combination with stitch-forming mechanism, of work-clamping means, said stitch-forming mechanism and work-clamping means having a movement relative to each other during a predetermined cycle of operations including a stitching operation, a thread clamp carried by said work-clamping means above the work, a cutter separate from the thread clamp, and means rendered operative by such relative movement to cause the thread clamp to clamp the thread at the end of the stitching operation and then to actuate the cutter to cut the thread and subsequently to actuate said thread clamp to unclamp the thread.
10. In a buttonhole sewing machine, the combination with stitch-forming mechanism, of work-clamping means, said stitch-forming mechanism and work-clamping means having a movement relative to each other during a predetermined cycle of operations including a stitching operation, a thread clamp carried by said work-clamping means above the work, a cutter separate from the

thread clamp, and means rendered operative at one point in said relative movement to cause the thread clamp to clamp the thread and then to actuate the cutter to cut the thread, and at another point in said relative movement to unclamp the thread.

11. In a sewing machine, the combination with stitch-forming mechanism, of work-clamping means, said stitch-forming mechanism and work-clamping means having a movement relative to each other during a predetermined cycle of operations including a stitching operation, a thread clamp carried by said work-clamping means above the work, a cutter separate from the thread clamp, and means rendered operative by such relative movement to cause the thread clamp to clamp the thread at the end of the stitching operation and then to actuate the cutter to cut the thread and to cause said thread clamp to release the thread at the beginning of the next succeeding stitching operation.

12. In a sewing machine, the combination with stitch-forming mechanism and work-clamping means, said stitch-forming mechanism and work-clamping means having a movement relative to each other during a predetermined cycle of operations including a stitching operation, two movable elements, one adapted to clamp and the other to cut the needle thread above the work held in the work-clamping means and means to actuate said elements successively at the end of the stitching operation whereby the thread will be first clamped and then cut and to actuate the thread-clamping element at the beginning of the next succeeding operation thereby to release said thread.

In testimony whereof, I have signed my name to this specification.

FRANK ZALESKI.
